BUTTON

Joseph Barratt, Naugatuck, Conn., assignor to
Scovill Manufacturing Company, Waterbury,
Conn., a corporation of Connecticut

Application October 20, 1933, Serial No. 694,468

5 Claims. (Cl. 24—95)

This invention relates to the type of metallic buttons which are secured to a garment or other article by means of a metallic fastener, and the specific form of the invention is represented in a 5 button having a hub that does not contain pre-formed openings for the passage of the attaching fastener, but in which the fastener is connected in setting position with the button head by driving the fastener legs or points through the unperforated hub bottom and against a clinching member which turns the legs or points of the fastener inwardly over the hub bottom between the perforations therein made by said legs. In this type of button the fastener is of 10 staple, that is to say of two-prong or two-legged form, in which in accordance with my invention the prongs are curled inwardly toward and overlapping one another side by side. In the type of button just described, it is common to supply the 15 bottom of the hub with an annular upstanding groove which serves to localize the entrance of the fastener points through the bottom of the hub.

The present invention is applicable equally to a closed top and an open top button. In the closed top button a combined filler and clinching anvil is made as a permanent part of the button, while in the open top button the structure of the button is such as to receive a movable setting die which is a thing apart from the button itself but which fits the button for the reception and clinching of its fastener.

In both the combined filler and anvil type and the extraneous die type a peculiarly shaped annular groove surrounding a seat is used by means of which the fastener has its points turned inwardly toward each other and set side by side with the points turned inwardly in opposite directions.

40 In the accompanying drawing illustrating the invention, in the several figures of which like parts are similarly designated, Figure 1 shows the several parts of a closed top button in position to be assembled. Fig. 2 shows the assembled 45 parts of Fig. 1 arranged on one side of an object to which the button is to be fastened and a staple-form fastener arranged on the opposite side in position to be inserted in the button. Fig. 3 is a cross section of the assembled parts, the near leg of the staple being broken away. Fig. 4 also 50 is a cross section of the assembled parts, the views in Figs. 3 and 4 being taken at right angles. Fig. 5 is a top plan view, and Fig. 6 is a bottom plan view of the combined filler and anvil of 55 Figs. 1 to 4. Fig. 7 is a top plan view, and Fig. 8

(Cl. 24—95) In this feature of the invention there is shown a hub having a hubbed back, the hub being shown cut to illustrate a bottom plan view of the hubbed back of the button of Figs. 1 to 4. Fig. 9 is a cross section of a closed top button in which the bottom of the hub is provided with an annular groove, and Fig. 10 is a bottom plan view thereof. Fig. 11 is a cross section illustrating an open top button with the setting die in position for connecting the button and fastener. Fig. 12 is an elevation of the leading portions of the die to set the open top button. Fig. 13 is a cross section of the open top button having its hub provided with the upstanding annular groove.

It will be understood from the drawing and the following description that the bottom of the hub may be made perfectly flat and straight as indicated in Figs. 1 to 4 and 11, or such hub bottom may be made with an annular upstanding groove as shown in Figs. 9, 10 and 13.

Without limiting the invention to any particular construction of closed top button or open top button, excepting as hereinafter claimed, and referring to the drawing, the back comprises a laterally extending flange 1 having the upturned marginal lip 2, and the straight walled hub 3 having the flat or straight bottom 4; a combined filler and anvil comprising the laterally extending flange 5 and the downwardly projecting cylindrical portion 6, the bottom of which includes the marginal wall 7 and the small centrally arranged inverted conical teat 8 between which parts 7 and 8 there is provided an annular groove 9 the walls of which slant inwardly on a curve of decreasing radius toward the teat 8; and a suitable cap 10 having the rim flange 11. The parts are assembled as shown in Fig. 2 by inserting the combined filler and anvil within the back so that its flange rests upon the flange 1 of the back and its cylindrical portion 6 extending well down toward the bottom of the hub and then the cap is applied by closing down its rim flange 11 over the lip 2, as shown in Figs. 2, 3, 4, 9 and 10, so as securely to unite the several parts.

As illustrated in Figs. 2, 3 and 4, a two-legged staple or fastener 12 of any approved construction is used, and its legs are driven through the article to which the button is to be attached, the points of the legs piercing the bottom of the hub and striking the marginal or outer wall 7 of the groove in the part 6 are turned crosswise and side by side and also toward the wall of the hub, as shown in Figs. 3 and 4 and in substantially close contact therewith and with the bottom of the hub. Meanwhile, the teat 8 serves to keep the points of the legs of the fastener separated while the process of rolling over these points is

progressing. In other words, the teat functions to prevent the abutting of the points of the legs of the fastener and ensure perfect rolling inwardly of the legs in the process of attaching.

5 The flange 5 of the combined filler and anvil practically fills the space between the flange 1 of the back and the cap 10 so that pressure used in applying the staple cannot distort the cap, and the cylindrical portion 6 practically fills the 10 inside of the hub 3 laterally and thereby preserves its cylindrical character.

15 In order to direct the piercing of the hub by means of the staple and to prevent dislocation of the legs of the staple, the bottom of the hub instead of being made entirely flat as in Figs. 1, 2, 3 and 4, may be provided with the annular upstanding groove 13, Figs. 9 and 10, and the points of the legs by this provision will enter the hub and strike against the curved side of the wall 7 20 of the combined filler and anvil and thus be accurately turned or rolled in by contact with the groove 9, same being crossed as indicated in Fig. 4 and turned outwardly toward the wall of the hub and its bottom, and at the same time coming 25 into contact with the teat 8 these points will be directed laterally away from one another, as shown in Fig. 4, thus preventing the butting together of the points and ensuring desirable rolling of the points to effect a secure connection between the staple and the button.

30 As shown in Fig. 11 the invention is applicable to an open top button, the difference between such open top button and the closed top button previously described being that the cap element 14 35 is centrally perforated and its edge turned down toward the hub 15 while its rim flange 16 is closed down over the upturned marginal lip 17 for assembly purposes. In the case of the open top button the previously described combined filler and 40 anvil is replaced by an extraneous die having the cylindrical portion 18 of a size to fit within the hub of the button and extend downwardly thereinto and provided with the teat 19 and the annular groove 20 corresponding in shape, construction and function with the parts designated 8 45 and 9 in the previously described closed top button. This die performs functions similar to the combined filler and anvil with respect to the closed top button. As shown in Fig. 11, the bottom of the hub may be flat or straight, or as 50 shown in Fig. 13 it may be provided with an annular groove 21 corresponding in function with the annular groove 13 previously described.

55 By the constructions of a closed top button and an open top button the dimensions of the hub need not be increased for the reception of the staple clinching features and thereby both forms of buttons may conform to the dimensions of these and other parts commonly used in standard buttons of these types. There is no tendency for distortion of the hub of the back and the cap.

60 As already stated, a function of the teat is to separate the staple legs in the process of rolling.

65 The relative size of the annular groove as compared to the distance between the staple legs is such that after the staple legs have pierced the hub, the points bear against the outside and inwardly sloping groove or annular groove in the anvil or die. It is impossible that the points of the staple be rolled outwardly because of the nature of the groove and the fact that the points are immediately turned inwardly. In the continued pressure of the setting dies or tools, the rolling or incurling of the staple legs continues and the 70 conical teat functions only to keep the staple legs

separated and from coming into intimate contact with one another and also to prevent them from shooting off to one side or the other because of lack of control. This conical teat functions in the process of rolling to ensure uniform results in the behavior of the staple legs. It is essential that the grooves in the combined filler and anvil or in the die should be of substantially the conformation shown rather than that the said grooves should be substantially circular 10 in cross section.

15 The use of a self-piercing fastener in connection with a button having initially an imperforate solid bottom in its hub, as in the present invention, effects economies in production and assembly, in that the utilization of the solid metal of the bottom of the hub between the holes made by the fastener in setting the parts, avoids the necessity of preparing a special cross bar or bridge for the anchorage of the fastener in the button, and 20 also obviates the necessity of providing a setting machine equipped to accurately assemble a fastener and a button already made with fastener holes so that the holes in the button and the points of the fastener may always register.

25 The term "anvil", as used in the claims, is intended to apply equally to the combined filler and anvil which is fixed in the closed top button and the extraneous die which takes its place in the open top button, since these two devices 30 function alike in the clinching of the staple legs.

35 There may be variations in the details of construction, excepting as hereinabove set forth and as expressed in the claims following.

What I claim is:

1. A button, provided with a back having a depending hub, and an anvil, the anvil having an annular groove of variable radii slanting inwardly toward the center, and a slight inverted conical teat centrally arranged, said button adapted to be set by means of a staple, the legs of which staple are driven through the bottom of the hub and coming into contact with the aforesaid groove are turned inwardly toward the teat and upon further pressure are separated laterally by the teat and inclosed within the hub and anchored upon the material of the hub between the legs of the staple.

2. A button, provided with a back having a depending hub, and an anvil, the anvil having an annular groove of variable radii slanting inwardly toward the center, and a slight inverted conical teat centrally arranged, said button adapted to be set by means of a staple, the legs of which staple are driven through the bottom of the hub and coming into contact with the aforesaid groove are turned inwardly toward the teat and upon further pressure are separated laterally by the teat and inclosed within the hub and anchored upon the material of the hub between the legs of the staple, the bottom of the hub provided with an upstanding annular groove adapted to initially guide the points of the staple as they enter the hub.

3. A button, having a combined filler and anvil, a hubbed back and a cap closed over the back, the combined filler and anvil secured between the back and the anvil extending into the hub and provided with an annular groove having an outside wall resting against the wall of the hub, said groove slanting inwardly toward the center, and a small inverted conical teat arranged centrally, the button adapted to be secured to an object by a staple having legs driven through the bottom of the hub and into contact with the interior of

the outer wall of the annular groove in the anvil and against the teat in the anvil, so as to roll the points of the staple inwardly away from one another, the teat serving to separate the legs of the staple so as to avoid abutting of its points.

4. A button, having a combined filler and anvil, a hubbed back and a cap closed over the back, the combined filler and anvil secured between the back and the anvil extending into the hub and provided with an annular groove having an outside wall resting against the wall of the hub, said groove slanting inwardly toward the center, and a small inverted conical teat arranged centrally, the button adapted to be secured to an object by driving the legs of a self-piercing staple through the bottom of the hub and into contact with the interior of the outer wall of the annular groove in the anvil and against the teat in the anvil, so as to roll the points of the staple inwardly away from one another, the teat serving to sep-

arate the legs of the staple so as to avoid abutting of its points, the bottom of the hub being provided with an annular upstanding groove which serves to guide the staple in its initial entry into the hub.

5. In a hubbed button, for use with a self-piercing staple fastener, an anvil provided with an annular groove slanting inwardly from the inside peripheral wall toward a centrally arranged inverted conical teat, the annular groove serving to deflect the points of the staple and roll them inwardly and curl the legs of the staple inwardly and toward the conical teat which teat serves to separate the points of the legs of the staple in the process of rolling, the annular groove and the teat cooperating to anchor the staple in the button hub against the material of the hub lying between the points of the staple.
